TION OF DELAWARE

HEAT EXCHANGER

Application filed April 20, 1931. Serial No. 531,297.

This invention relates to heat exchangers and particularly to heat exchangers adapted for cooling or vaporizing liquids.

In apparatuses of the aforesaid type a liquid medium is passed over a plurality of tubes, through which is circulated another liquid medium of a different temperature. In the usual practice, the liquid medium passed over the tubes is often of such chemical nature, as to form a hard crystalline deposit on the surface of the tubes. The accumulation of this deposit, insulates the pipes and acts to prevent the transfer of heat therefrom, thus seriously interfering with the economical and efficient operation of the apparatus.

The principal object of the present invention is to provide a heat exchanger tube unit which will operate to remove the aforementioned deposit from the surfaces of the tubes by its own movement so as to insure at all times, clean tube surfaces and to effect a maximum efficiency of operation of the apparatus. In the attainment of this object there is eliminated the usual expensive method of hand removing the deposit from the tubes which method requires the lengthy shutdown of the apparatus during the performance of this operation.

The invention is illustrated in the accompanying drawings in which Figure 1 is a plan view of a heat exchanger tube unit embodying the present invention; Fig. 2 is a longitudinal section taken on the line II—II of Fig. 1; Fig. 3 is a transverse section taken on the line III—III of Fig. 1; Fig. 4 is an end view of the guide plates; Fig. 5 is an end view of the embodiment shown in Fig. 1; Fig. 6 is a vertical section of a cooling tower, embodying the exchanger tube unit of this invention taken on the line VI—VI of Fig. 7; Fig. 7 is a side elevation of half of the tower shown in Fig. 6; and Fig. 8 is a longitudinal section of an evaporator embodying a modified form of the exchanger tube unit of this invention.

Referring descriptively to the drawings, the improved heat exchanger tube unit of this invention (Figs. 1 to 5) comprises a pair of oppositely disposed tube sheets 1 and 2,

into which are expanded, or otherwise fitted, the respective ends of a plurality of spaced, parallel, straight tubes 3. The tubes are preferably of non-ferrous metal. At the centers of the tubes a pair of aligned guide plates 4 and 5 are located. The tubes pass through orifices formed in the guide plates and are held in their relative positions thereby, and divided into two separate groups. Adjacent the tube sheets 1 and 2, heads 6 and 7 are disposed. The heads comprise substantially, box-shaped members having flanges formed at the inner and outer ends. The inner flanges 8 and 9 of the heads 6 and 7, respectively, are bolted to the tube sheets 1 and 2, corresponding orifices being formed in the flanges and the peripheries of the tube sheets, and bolts 10 and 11 being passed therethrough, and being provided with nuts at their ends. Over the outer ends of the heads 6 and 7, and adjacent the outer flanges 12 and 13 of the respective heads, cover plates 14 and 15 are disposed. The cover plates are bolted to the flanges 12 and 13 in the same manner as the flanges 8 and 9 are bolted to the tube plates, corresponding orifices being formed in the flanges 12 and 13 and in the peripheries of the cover plates and bolts 16 and 17 being passed therethrough, and provided with nuts at their ends. Within the head 6, a transverse wall 18 is provided, thus dividing the head into two separate compartments. A flanged inlet opening 19 is provided on one side of the head 6 affording communication to one of the compartments, and a flanged outlet opening 20 is provided on the opposite side of the head affording communication to the other compartment. A steam inlet port 21 is also provided in the side of the head 6 on the inlet side of the same.

Pairs of tie-rod sections 22 and 23 are provided for each group of tubes both above and below the same. The outer ends of the tie-rod sections 22 are tapped into holes formed in the tube sheet 2, and the outer ends of the tie-rod sections 23 are tapped into holes formed in the tube sheet 1, the sections being thereby secured to the tube sheets. The pairs of the tie-rod sections are

100

normally slightly inclined to the tubes. The inner ends of the sections 23 are bifurcated and the inner ends of the sections 22 are flattened to engage the bifurcated ends and bolts 5 24 are passed through the said engaged ends and a hinged joint between the sections 22 and 23 is thereby provided whereby the hinged inclined rod sections may swing in their plane. Each of the tie-rod sections is 10 severed at its center and provided with a turn buckle 25 by means of which the tie-rods may be adjusted to the desired length. On the upper and lower sides of the guide plates 4 and 5 depressions 26 are formed, 15 through which the tie-rods pass, and knife edge projections 27 are provided at the sides of the depressions, the edges of the projections bearing upon the hinged joints of the tie-rod sections and normally holding the sections in a slightly angular or inclined position.

In the operation of the exchanger tube unit liquid will be introduced through the inlet opening 19 to the compartment on the inlet side of the head 6. The liquid will 25 then pass through the tubes which communicate with the aforesaid compartment and into the head 7 at the opposite end of the tubes. The liquid will then pass back through the tubes which communicate with 30 the compartment on the outlet side of the head 6, and will then pass out through said outlet opening.

When the removal of deposit formed on the surface of the tubes is desired, the inlet 35 port 19 is closed, and steam is introduced through the port 21 and passes through the unit in the same manner as aforescribed with reference to the liquid passing out through the outlet port 20. The tubes, due 40 to their being heated by the steam passed therethrough, are caused to expand or elongate thereby effecting a slight outward movement of the tube sheets. The tube sheets being secured to the outer ends of the tie-rods, 45 carry the rods with them in their outward movement, and effect the straightening out of the rods from their angular positions. The tie-rods, bearing on the projections as aforescribed, in straightening out from 50 their angular positions, spread the guide plates apart and thereby carry the central portions of the opposite groups of tubes outward, causing a slight bowing of the tubes. When the tie-rods have reached a straight 55 line position, further outward movement of the tube sheets will obviously be prevented, and any additional increase of elongation of the tubes will result in their further outward bowing to a relatively considerable extent. When the flow of steam through the 60 unit is discontinued and the temperature of the tubes thereby reduced, the tubes contract, returning to their normal straight line positions, and the tie-rods are returned to their 65 initial slightly angular positions. The alter-

nate bowing and straightening out of the tubes and the consequent variation of the areas of their surfaces will cause the deposits on the surfaces to flake off, leaving the tubes clean and free of the undesirable coating. 70

A decided advantage is achieved by the aforescribed operation by virtue of the tubes being normally straight and the bowing of the same beginning from the straight line position. To effect the initial bowing requires but a relatively slight initial elongation and there is required therefore, only a relatively small increase in temperature. Heretofore structures have been designed for purposes similar to that 80 of the instant invention, wherein sets of permanently bowed tubes have been employed. The present arrangement constitutes a substantial improvement over such designs due to the aforementioned fact that 85 the nearer the tubes are to this straight line position the greater is the amount of bowing effected by each unit of elongation. Conversely, the further away from the straight line position, that is, the more curvature there 90 is to the tube, the less is the bowing effected by each increment of elongation. When a curvature angle of 45° is reached the bowing is equal to one half the elongation, that is to say, for each given unit of elongation of the 95 tube, the tube will bow one half of that unit. In direct proportion, bowing is effected in the intermediate positions between the angle of 45° and the straight line with a gradual 100 relatively greater amount of bowing for a unit of elongation as the tube straight line position is approached.

Many and various structural advantages are also incident to the employment of a straight tube in preference to a permanently 105 curved one. In the first mentioned structure all of the tube holes may be drilled directly square to the tube sheet and only a single set up is required for such operations. Likewise in the use of the straight tube the 110 labor and expense involved in the curving of a tube for the other type of structure is eliminated.

In Figs. 6 and 7 there is illustrated a typical application of the heat exchanger tube unit hereinbefore described to an atmospheric type of cooling tower. This tower is of the usual type and construction, embodying a plurality of sprinklers 28 at the top of the tower, and a series of cooling screens 29 disposed one above the other. The heat exchanger unit of this invention indicated generally by the numeral 30, is horizontally disposed across the lower portion of the tower and a distributing pan 31 is located immediately above the unit, and below the cooling screens. 115

In the operation of the tower cooling water is pumped from a collecting trough 32, which is located at the base of the tower, to 120

the sprinklers 28, by means of a pump (not shown) which is disposed between the pipes 33 and 34 which are respectively connected to the trough and the sprinklers. The water 5 passes from the sprinklers down through the screens 29, being cooled in its downward path, as in usual practice by the passage of air through the tower. The cooling water falls over the perforated distributing pan 31 10 and is distributed over the tubes of heat exchanger tube unit 30, passing on to the collecting trough 32, whereupon the cycle is repeated. In the cooling tower illustrated, four heat exchanger tube units are employed, the 15 fluid to be cooled being circulated through the units and the bowing of the tubes for the purpose of removing deposits therefrom being effected when desired, as described with reference to Figs. 1 to 5.

20 In Fig. 8 there is illustrated an application of the heat exchanger tube unit of this invention to a standard type of evaporator. The evaporator comprises an outer shell indicated generally by the numeral 40, which 25 shell is provided with inlet ports 41 and outlet port 42. The heat exchanger tube unit is horizontally disposed within the shell 40, an opening 43 being provided in one end of the shell through which the tube unit is inserted 30 and removed. A flanged collar 44 is provided around the periphery of the opening 43. The periphery of the tube sheet 45 at the outer end of the tube unit, is adjacent the flanged collar 44. In this construction of the 35 tube unit, modified forms of heads are employed. The head 46 comprises a dome shaped casting having a transverse wall 47 formed therein, dividing the head into relatively large and small respective upper and 40 lower compartments. An inlet port 48 is provided in the upper compartment and an outlet port 49 is provided in the lower compartment. The head 46, tube sheet 45 and collar 44 are secured together by bolts not shown. 45 At the opposite end of the tube unit a dome shaped head 50 is provided. The head 50 is formed with a peripheral flange 51 and is secured to the tube sheet 52 by bolts not shown. A compartment is thus provided at 50 this end of the unit into which all of the tubes open. This end of the unit is free for longitudinal motion as the tubes expand or contract. Transverse beams 53 and 54 are provided for supporting the unit while permitting the same to slide longitudinally thereon. A port 55 having a suitable removable cover 56 is provided in the lower portion of the tank, as in usual practice, for removing deposits and affording access to the 55 interior of the shell.

60 In the operation of the vaporizer, heating fluid is introduced to the exchanger tube unit through the port 48 and passes through the tubes in substantially the same manner as described with reference to the former struc-

ture, passing out through the outlet port 49. By reason of the upper compartment being larger than the lower one in the head 46, the heating fluid while at its highest temperature will be passing through the tubes toward the head 50, and while at its lowest temperature will be passing back toward the head 46, and thus the fluid while at a high temperature will be passing through a greater number of tubes than while at a lowered one, thereby effecting the greatest possible heat exchange. Liquid to be vaporized is introduced into the shell through the inlet ports 41 where it circulates around the tubes 3, and vapor which is formed by the exchange of heat, passes out through the outlet port 42. Bowing of the tubes for the purpose of removing deposit formed thereon may be effected either by introducing steam into the tubes, through the opening 48 or by simply varying the temperature of the heating fluid passed therethrough. When desired a separate port, similar to port 21, may be formed in the head 46 for separately introducing steam.

65 While there has been hereinbefore described specific embodiments of the instant invention it will be understood that many and various changes and modifications in form, procedure, details of construction and applications of the invention may be made without departing from the spirit of the invention, and it will be understood that all and any such changes and modifications as fall within the scope of the appended claims are contemplated and are to be considered as a part of the instant invention.

70 What we claim as new and desire to secure by Letters Patent is:

1. In a heat exchanger, the combination of a straight tube, adapted for the circulation of fluid therethrough; and means for automatically effecting curvature of said tube when the same is elongated by the application of heat thereto.
2. In a heat exchanger, the combination of a plurality of straight, parallel, spaced tubes, adapted for the circulation of fluid therethrough; and means operatively connected to said tubes for automatically effecting curvature of the same when said tubes are elongated by the application of heat thereto.
3. In a heat exchanger, the combination of a normally straight tube adapted for the circulation of fluid therethrough; bending means adjacent said tube normally held in an angular position; means connecting said tubes and said bending means at the respective ends thereof; and means operatively connecting said tube with said bending means between said respective ends, whereby said bending means will be moved from angular position to straight line position and will effect a curvature of said tubes when the same

is elongated by the application of heat thereto.

4. In a heat exchanger, the combination of a plurality of normally straight tubes arranged in spaced parallel relation and adapted for the circulation of a fluid therethrough; bending means adjacent said tubes normally held in an angular position; connecting means between said tubes and said bending means at the respective ends thereof; and means operatively connecting said tubes with said bending means between the said respective ends, whereby said bending means will be moved from angular to straight line position and will effect a curvature of said tubes when elongation of said tubes is caused by the application of heat thereto.
5. In a heat exchanger, the combination of a plurality of normally straight tubes, adapted for the circulation of fluid therethrough; a tube plate at each of the opposite ends of said tubes securing the same in their relative positions; tie members secured to said tube plates said tie members being normally held in angular positions; and means disposed between the said tube plates, operatively connecting said tubes and said tie members, whereby upon elongation of said tubes caused by the application of heat thereto, said tube plates will be moved outwardly effecting a straightening of said tie members and causing curvature of said tubes, and whereby said tube plates will be held in fixed spaced relation when said tie members have reached straight line positions and further elongation of said tubes will effect further curvature of the same while their ends are held in fixed spaced relation.
6. In a heat exchanger, the combination of a plurality of spaced, parallel, normally straight tubes; compartments disposed at the opposite ends of said tubes, adapting the same for the circulation of fluid therethrough, each of said compartments comprising a tube plate on its inner end in which the ends of said tubes are secured, a substantially box shaped body portion, and a cover disposed over its outer end, tie members having ends secured in said compartments and normally held in angular positions; and means, disposed between the tube plates, operatively connecting the tubes and tie members, whereby upon elongation of said tubes, caused by the application of heat thereto, said tube plates will be moved outwardly to effect the straightening of said tie members from their angular positions and curvature of said tubes will be effected.
7. In a heat exchanger, the combination of a plurality of spaced, parallel, normally straight tubes adapted for the circulation of fluid therethrough; a tube plate disposed at each of the opposite ends of said tubes securing the same in their relative positions; a guide plate disposed between said tube plates holding the central portions of said tubes in their respective positions, the said tubes passing through orifices formed in said guide plate; tie members secured to said tube plates and normally held in angular position; and means on said guide plate operatively connecting the same with said tie members, whereby upon elongation of said tubes caused by the application of heat thereto, said tube plates will be moved outwardly to effect the straightening of said tie members from their angular positions and curvature of said tubes will be effected.
8. In a heat exchanger, the combination of a normally straight tube adapted for the circulation of fluid therethrough; tying means adjacent said tube normally held in an angular position; a second normally straight tube adapted for the circulation of fluid therethrough; parallel to the first mentioned tube; tying means adjacent said second tube normally held in an angular position; means at the respective ends of said tubes and said tying means securing the same together; and means between said ends operatively connecting said tubes and their said adjacent tying means, whereby upon elongation of said tubes by the application of heat thereto said end connecting means will be moved apart and said angular tying means will be moved to a straight line position effecting a curvature of said tubes.
9. In a heat exchanger, the combination of a plurality of spaced, parallel, normally straight tubes; tube plates disposed at the opposite ends of said tubes holding the same in their relative positions; a plurality of tie members connected to said tube plates and normally held in angular positions; and means disposed between said tube plates connecting said tie members with said tubes whereby upon elongation of said tubes by the application of heat thereto, said tube plates will be moved outwardly to effect the straightening of said tie members from their angular positions and a curvature of said tubes will be effected.
10. In a heat exchanger, the combination of a plurality of groups of spaced, parallel, normally straight tubes; tube plates disposed at the opposite ends of said tubes, holding the same in their spaced relation; a guide member for each group of tubes disposed between said tube plates holding the same in their relative spaced positions; tie members for each group of tubes connected to the tube plates and normally held in angular positions; and means for each group of tubes operatively connecting its said guide member and said tie member, whereby upon elongation of said tubes by the application of heat thereto said tube plates will be moved apart and said tie members will be moved to

straight line positions and curvature of said tubes will be effected thereby.

11. In a heat exchanger, the combination of a plurality of groups of parallel, spaced, 5 normally straight tubes; a tube plate disposed at each of the opposite ends of said tubes, securing the same in their relative positions; a guide plate for the tubes of each of said groups, said guide plate having a plurality of orifices formed therein through 10 which said tubes are passed; tie members for each group of tubes connected with said tube plates, said tie members having hinged connections adjacent said guide plates and being normally held in angular positions; and 15 means on said guide plates operatively connecting the same to the tie members of their respective groups, whereby upon elongation of said tubes by the application of heat there- 20 to, said tube plates will be outwardly moved and said tie members will be moved to straight line positions, effecting the curva- 25 ture of said tubes.

12. In a heat exchanger, the combination 25 of a plurality of spaced, parallel, normally straight tubes; substantially box shaped head members disposed at the opposite ends of said tubes having tube plates on their inner sides, said tube plates holding the ends of said 30 tubes in their relative positions, and said head members having cover plates disposed on their outer sides, one of said head members having a transverse wall formed therein dividing the interior of same into two sections, and 35 an inlet port formed in one section of said head member and an outlet port formed in the other section, whereby a fluid may be circu- 40 lated through said head members and tubes; and tie members secured to said tube plates normally held in an angular position 45 and operatively connected to the central portions of said tubes, whereby upon elongation of said tubes by the application of heat there- 50 to, said head members will be moved apart and said tie members will be moved to straight line position effecting the curvature of said tubes.

13. In a heat exchanger, the combination 50 of a plurality of spaced, parallel, normally straight tubes; substantially box shaped head members disposed at the opposite ends of said tubes, having tube plates secured on their inner sides, said tube plates holding the ends of the tubes in their relative positions, 55 and said head members having cover plates disposed on their outer sides, one of said head members having a transverse wall formed therein dividing the interior of same into two sections, and an inlet port formed in one 60 section of said head member and an outlet port formed in the other section, whereby fluid may be circulated through said head members and tubes; and tie members secured to said tube plates normally held in an angular 65 position and operatively connected to the

central portions of said tubes, whereby upon elongation of said tubes, by the application of heat thereto, said head members will be moved apart and said tie members will be moved to straight line position effecting the 70 curvature of said tubes, and said divided head member having a steam port formed therein for the introduction of steam into the same.
